SOLE ATTACHING APPARATUS

John T. Lancaster, Newton, Mass., assignor to
 United Shoe Machinery Corporation, Paterson,
 N. J., a corporation of New Jersey

Application December 30, 1932, Serial No. 649,520

10 Claims. (Cl. 12—33)

This invention relates to sole attaching apparatus, and is herein set forth by way of illustration with particular reference to apparatus for applying sole attaching pressure to an assembly consisting of a lasted shoe and a sole which are to be attached to each other by cement.

The illustrated embodiment of the invention has been developed with especial reference to the problem of supporting the sole extension and preventing it from becoming rounded by the attaching pressure in the manufacture of shoes in which the sole is larger in its forepart than the corresponding portion of the bottom of the last and, consequently, extends beyond the periphery of the shoe. A typical example of such a sole extension is found in a man's ordinary welt shoe, wherein the welt and sole extend outward beyond the lasted upper and require mechanical support during the cement sole attaching operation, not only to prevent the sole margin from becoming rounded but also to cause the welt and sole to be pressed together with sufficient force to ensure adequate bonding of one to the other. The invention, therefore, is particularly important as an aid in the cement attachment of soles to welt shoes, but its utility is not limited exclusively to welt work nor to cement attachment, since it may be employed advantageously in connection with any shoe having a sole extension, whether welted or not, and without regard necessarily to the particular method by which the permanent attachment of the sole is effected.

It is an object of the invention to provide improved apparatus of simple construction which shall be capable of effectively and accurately supporting a projecting welt or sole extension against the pressure which is applied when a sole is attached by the cement process.

The invention is illustrated as embodied in pressure applying apparatus for a sole attaching machine in which is incorporated a sole extension support a side portion of which is arranged to be removed far enough from operative position to permit a shoe to be inserted sidewise and positioned easily, combined with means for moving said support between operative and inoperative positions.

The sole extension support may comprise a plurality of relatively movable members which together conform to the outline of the forepart of a shoe, and portions of said support which engage opposite sides of the shoe may be geared together for simultaneous equal and opposite movement, about axes extending longitudinally of the

shoe, toward or away from operative position or, alternatively, only one side portion of the support may be arranged to swing outward to provide a free space for sidewise insertion of a shoe, while the other is normally stationary and serves, in addition to its supporting function, as a shoe positioning gage.

The invention further contemplates, for a sole attaching machine, a simple and effective self-contained pressure applying unit in which are combined a pad box, a pressure pad in the pad box, a yoke arranged over the pad and supported by the pad box, and a sole extension support mounted upon a toe rest, which is also sustained by the yoke, and, since it is desirable that the toe rest be slightly yielding in order to avoid marring the shoe being operated upon, the support may be arranged to yield correspondingly, to the end that proper relation between the toe rest and the sole extension support shall be maintained during the application of pressure.

The foregoing and other features and advantages of the invention will be better understood and appreciated from reading the following detailed description of a specific embodiment and a modification thereof in connection with the accompanying drawings, in which

Fig. 1 is a view, partly in side elevation and partly in longitudinal section, of a simple form of pressure applying apparatus embodying the invention;

Fig. 2 is a cross sectional view upon the line II—II of Fig. 1;

Fig. 3 is a view partly in side elevation and partly in longitudinal section of a modified form of the invention; and

Fig. 4 is a sectional view, similar to Fig. 2, upon the line IV—IV of Fig. 3.

In the embodiment of the invention illustrated in the drawings 10 indicates a pad box, preferably of metal, containing an inflatable pressure pad 12 which, as shown, comprises a rubber bag 14 which is fluid-tight and is encased by a cover 16 which may be of leather or other suitable material. It will be understood that provision will be made, in a manner well known in the art, as by a valve 17, for admitting and allowing the escape at will of water or compressed air, in order to inflate or deflate the pad.

A yoke 18 is supported by the pad box 10, being preferably rigid therewith, and extends through the entire length of the pad box above the pad. Sustained by the said yoke 18 are a toe rest 20 and a heel rest 22 mounted upon the lower ends of posts 24 and 26 respectively which

depend from the yoke. It will be apparent to those skilled in the art that when a lasted shoe and an outsole are assembled upon the pad 12, with the toe portion of the shoe beneath the toe rest 20 and the cone of the last beneath the heel rest 22, and the pad is inflated the sole will be pressed closely upon the shoe.

Referring to Figs. 1 and 2, wherein is shown one embodiment of a sole extension and welt support, 28 and 30 indicate a pair of meshed gear segments which are secured to arms 32 and 34 respectively mounted upon pivots 36, 38 for opposite, transverse, swinging movement about horizontal axes extending longitudinally of the shoe 40 which is shown in pressure applying position.

The arms 32, 34 support the side portions 42, 44, respectively, of a sole extension engaging support which, as a whole, may be considered as consisting of the two elements 42, 44 taken together. When the parts are in operative position, as illustrated in Figs. 1 and 2, the sole extension engaging portions 42, 44 conform substantially to the shape of the forepart of the shoe and are vertically immovable by reason of the fact that their pivotal supports 36, 38 are mounted in the toe post 24 which in turn is sustained by the rigid yoke 18.

Each of the work engaging elements 42, 44 has a face 46 adapted to engage the upper face of the sole extension or welt of the shoe and support the same against upward pressure, and a vertical face 48 adapted to engage the edge of the outsole 50 of the shoe and of the welt 52, if there is one, for the purpose of securing proper positioning of the shoe elements with respect to each other and to the pressure pad 12.

The arm 34 is provided with a handle 54 by means of which it may be swung outward and upward to a position remote from its operative position to permit the shoe to be inserted sideways without impediment. In this embodiment of the invention both side portions of the sole extension support are swung outward simultaneously equally and oppositely by reason of their connection through the gears 28, 30.

In order to provide for shoes of widely different sizes or shapes, the elements 42, 44 are mounted upon the arms 32, 34 in a manner to permit their ready removal therefrom and the substitution of other similar elements of different contours. As shown, this is accomplished by pins 56 threaded into the removable elements and having circumferential grooves near their outer ends in which engage retaining latches 58 which may be easily swung aside to permit the sole extension supporting elements to be readily detached from their mountings.

Referring now to the modified form of the invention illustrated in Figs. 3 and 4, wherein the same reference characters are used to designate elements which are common to this embodiment of the invention and that illustrated in Figs. 1 and 2, the rear side portion 42 of the sole extension support is, in this case, normally stationary, only the front side portion 44 being arranged to be swung outward.

Here the toe post 24 carries a pair of stationary horizontal studs 60 disposed transversely of the pad box and constituting guides for slidable carriers 62 which sustain the parts of the sole extension support.

Also mounted in the toe post 24, but freely rotatable therein, is a right and left screw 64 endwise movement of which is prevented by col-

lars 66 pinned to the screw at opposite sides of the toe post. Threaded upon the right and left threads of the screw 64 are two nuts 68, 70 having flanges 72 which are received in slots cut in lugs 74 extending upward from the carriers 62. Set screws 76 serve to secure the flanges 72 firmly to the carriers 62 so that rotation of the screw 64, by means of the hand wheel 78 which is secured thereto, will cause the carriers 62 to be simultaneously and equally adjusted toward or from each other. Under some circumstances, however, it may be desired to adjust one carrier with its attached sole engaging member independently of the other and this may be readily accomplished by loosening the set screw 76 of the carrier which it is desired to adjust and then turning the nut 68 or 70, as the case may be, while holding the screw 64 against rotation. When the desired independent adjustment has been secured the set screw 76 may be tightened and the offset relation produced by the independent adjustment will be preserved during subsequent equal and opposite adjustments which may be effected by turning the screw 64.

The front carrier 62 has bearings 80 in which is journaled a shaft 82 extending longitudinally of the shoe 40 and having secured to it a handle 84 by which it may be rocked. A series of sleeves 86 which support the work engaging element 44 are secured rigidly to the shaft 82 so that when the shaft is rocked the element 44 may be swung outward and upward to provide a free space to permit sidewise insertion of the shoe beneath the toe rest 20.

In order to permit the sole extension supporting element 44 to be locked either in operative position or in an elevated inoperative position, notches 88 are provided in a stationary disk 90 surrounding the shaft 82 and held against rotation by an arm 92 having its end anchored by a stationary rod 94 which extends from the front portion of the yoke 18 to the toe post 24. A spring pressed latch pin 96 slidably mounted in the handle 84 is adapted to engage in either notch 88 and to be retracted by a finger-operated lever 98 to permit the shaft 82 to be rocked, all as clearly shown in Fig. 4.

The rear carrier 62 is provided with a series of sleeves 100 which are like the sleeves 86 and are rigid with the carrier. The work engaging elements 42, 44 are carried by rods 102 which are vertically slidable in the sleeves 86, 100, and upon the upper ends of which are threaded nuts 104 by means of which the positions of the rods in the sleeves may be adjusted, stiff springs 106 being interposed between the lower ends of the sleeves and the work engaging members to support the upward pressure upon the sole extension or welt of the shoe. The rods 102 preferably fit very loosely in the sleeves 86, 100 in order that the longitudinal tilt of the work engaging element may be varied somewhat by adjustment of the nuts 104.

Inasmuch as it is desirable that the toe rest 20 be made of material which will yield somewhat in order to avoid marring the shoe, the strength of the springs 106 is so selected that the welt support will yield correspondingly, to the end that the proper relation between the support and the shoe shall be preserved when pressure is applied.

Inasmuch as the toe post 24 is stationary, means may be provided for adjusting the heel rest 22 to lasts of different sizes. Referring to Fig. 3 the heel post 26 is carried by a slide 108

movable upon longitudinal guides 110 formed upon the yoke 18, an adjusting screw 112 being provided for effecting adjustment longitudinally of the yoke and the pad. The heel rest 22 is 5 vertically adjustable with respect to the post 26 by means of a right and left screw 114, a guide pin 116 being provided to prevent rotation of the heel rest. This simple arrangement permits the heel rest to be adjusted both longitudinally and 10 vertically through ranges sufficient to accommodate the different lasts to be used.

Having thus described my invention, what I claim as new and desire to secure by Letters Patent of the United States is:—

15 1. Pressure applying apparatus for a sole attaching machine, comprising a sole extension support conforming to the forepart of a shoe, said support having a sole extension engaging side portion adapted to be removed far enough 20 from operative position to permit a shoe to be inserted sidewise, and means for moving said side portion between operative and inoperative positions.

25 2. Pressure applying apparatus for a sole attaching machine, comprising a sole extension support having oppositely movable side portions which together conform to the forepart of a shoe and which are geared together for simultaneous movement from operative position to positions 30 remote therefrom.

35 3. Pressure applying apparatus for a sole attaching machine, comprising a sole extension support conforming to the forepart of a shoe, said support having a side portion adapted to be swung outward and upward about an axis extending longitudinally of the shoe to provide a clear space for the insertion of the shoe, and means for varying the position of said axis transversely of the shoe.

40 4. Pressure applying apparatus for a sole attaching machine, comprising a sole extension support having opposite side portions which together conform to the forepart of a shoe, each of said side portions being adjustable transversely of the shoe independently of the other, combined with means for effecting simultaneous equal and opposite adjustment of said side portions toward or from each other.

45 5. Sole attaching apparatus, comprising a pressure pad, a toe rest, sole extension support-

ing members one of which is fulcrumed upon a horizontal pivot and arranged to engage the sole extension when in operative position, and means for swinging said member about its pivot to an inoperative position remote from the pressure 5 pad, to permit the sidewise insertion of a shoe between the pad and the toe rest.

6. Pressure applying apparatus for a sole attaching machine, comprising a pad box, a pressure pad therein, and a sole extension support 10 conforming to the forepart of a shoe, said support being sustained above the pad and comprising a normally stationary side portion constituting a combined sole extension support and shoe positioning gage and an opposite side portion 15 which is outwardly movable to a sufficient extent to afford free access to the pad for sidewise insertion of a shoe to a position determined by said gage.

7. A self contained pressure applying unit for 20 a sole attaching machine comprising a pad box, an inflatable pressure pad in the pad box, a rigid yoke arranged over the pad and supported immovably upon the pad box, a slightly yielding toe rest fixedly supported by the yoke, and a 25 correspondingly yielding sole extension support disposed around the toe rest.

8. Sole attaching apparatus, comprising a pad box, an inflatable pressure pad in the box, a yoke fixedly mounted on the pad box and extending 30 over the pad, a sole extension supporting member conforming to the forepart of a shoe movably mounted upon the yoke, and means for moving said supporting member transversely of the pad from an operative position over the pad to 35 an inoperative position remote from the pad.

9. Sole attaching apparatus, comprising a pad box, an inflatable pressure pad in the pad box, a toe rest arranged over the pad and supported in fixed relation to the pad box, and a sole 40 extension support mounted upon the toe rest.

10. Sole attaching apparatus, comprising a pad box, an inflatable pressure pad in the pad box, a toe rest arranged over the pad and supported in fixed relation to the pad box, and a sole 45 extension support mounted upon the toe rest, said sole extension support comprising side portions which are oppositely movable transversely of a shoe upon the pad.

JOHN T. LANCASTER. 50
